UNITED STATES PATENT OFFICE.

IRA BRINDLE, OF MARKES, PENNSYLVANIA.

DESIGN FOR A STRAINER-BOX.

SPECIFICATION forming part of Design No. 26,225, dated October 27, 1896.

Application filed July 10, 1896. Serial No. 598,756. Term of patent 7 years.

To all whom it may concern:

Be it known that I, IRA BRINDLE, a citizen of the United States, residing at Markes, in the county of Franklin and State of Pennsylvania, have invented and produced a new and original Design for a Strainer-Box, of which the following is a specification, reference being had to the accompanying drawings.

Figure 1 is a side view of the box. Fig. 2 is a cross-section taken on the line *x x* in Fig. 1.

The leading feature of my design consists of a hollow oblong box open at the top and provided with an opening located at the lower part of one of the longer sides of the box at about equal distances from its ends, and having a projecting boss about the said opening on the outside of the box.

A is the hollow oblong box, which is open at the top.

B is the boss arranged on the outside of the box around the opening *c*, which is located at the lower part of one of the longer sides *a* at about equal distances from the ends *a'* of the box.

What I claim is—

The design for a strainer-box substantially as herein described and shown.

In testimony whereof I affix my signature in presence of two witnesses.

IRA BRINDLE.

Witnesses:

A. B. LOUDERBAUGH,
C. N. FALLON.
